UNITED STATES PATENT OFFICE.

FRANKLIN O. MACKEY, OF TUCSON, ARIZONA.

TOOL FOR SLOTTING A WELL-CASING.

1,189,984.

Specification of Letters Patent.

Patented July 4, 1916.

Application filed March 26, 1915. Serial No. 17,216.

To all whom it may concern:

Be it known that I, FRANKLIN O. MACKEY, a citizen of the United States, residing at Tucson, in the county of Pima and State of Arizona, have invented certain new and useful Improvements in Tools for Slotting a Well-Casing; and I do hereby declare the following to be a full, clear, and exact description of the invention, such as will enable others skilled in the art to which it appertains to make, and use the same.

This invention relates to new and useful improvements in tools for slotting well casings, and has for its principal object to provide a device which will cut two or more slots in a well casing simultaneously.

Another object of the invention is to provide a device which may be let in through the well casing from the upper end to the proper distance within the casing and set in operation from the outside of the well.

With these and other objects in view, the invention consists in the novel combination and arrangement of parts which will be fully set forth in the following specification and accompanying drawings, in which,

Figure 1 is a sectional view of a well casing and tool constructed in accordance with this invention, showing the same as it would appear when entering the well casing, Fig. 2 is a view similar to Fig. 1 showing the device as it would appear after having cut the slots in the casing, Fig. 3 is a sectional view taken on line 3—3 of Fig. 2, Fig. 4 is a view in elevation of the guide blocks for the cutting rollers, Fig. 5 is a detail perspective view of one of the blocks carrying the cutting rollers, and Fig. 6 is a side view in elevation of the wedge member which controls the operation of the cutting rollers.

Referring now to the drawings by characters of reference, the numeral 1 designates the well casing in which the tubular member 2 is slideable. This tubular member 2 is turned at each end as at 3 and carries intermediate of its ends the guide block 4 which is best illustrated in Fig. 4. This guide block comprises the cylindrical body portion 5 having the tapered central aperture 6 formed therein. This aperture extends axially with relation to the cylindrical body and has communicating therewith the transverse slots 7 in which the blocks carrying the cutting rollers are slideable.

These blocks, referred to in the above paragraph, are designated generally by the

numeral 8, and are best illustrated in Fig. 5, and each of said blocks comprises the body 9 having formed therein an end recess 10 in which the cutting wheel 11 is mounted to 60 rotate on the pin 12. This cutting wheel 11 is provided with a suitable cutting edge 13 as clearly shown in the drawings. The body 9 is provided on the side opposite the recessed side, with the beveled face 14, which is 65 arranged to engage the tapering wedge member, which will be more fully hereinafter described. A groove 15 is formed near the face 14 and extends parallel therewith and said groove is arranged to coöperate with the 70 wedge member hereinbefore referred to in holding the device in proper position. A similar groove 16 is formed on the opposite side of the body 9 and also extends parallel with the face 14 as illustrated in the drawings.

The wedge member, hereinbefore referred to, is designated generally by the numeral 17 and comprises the cone-shaped body 18 having formed at its enlarged end the enlarged 80 cylindrical portion 19, the opposite end of which terminates in the cone-shaped portion 20, having formed at its reduced end the cylindrical extension 21, which is provided with the cylindrical enlargement 22 which in 85 turn carries the threaded cylindrical portion 23, to which the jar or other driving device is threaded.

The body 18, hereinbefore referred to, is provided with the longitudinal grooves 24 90 which are enlarged at their inner terminals as illustrated in Fig. 3 to receive the flanges formed by the grooves 15 and 16 on the roller-carrying members 8. These grooves 24 are provided with the enlarged opening 95 25 at their lower terminals by which the blocks 8 carrying the cutting wheels 11, may be put in place or removed from the wedge member 17. A cylindrical extension 26 is formed at the reduced end of the body 100 of the wedge member and said extension is provided with the slot 27, through which the pin 28 extends. This pin 28 is provided with a suitable cotter pin 29 for retaining the same in place and forms a support for 105 the disk 30, which forms the lower abutment for the device, against which the member 4 rests, when the device is being put in place or removed from the well casing.

In order to hold the device in the proper 110 place in the well casing, there is provided the extension 31, which is riveted or other-

wise secured as at 32 to the tubular member 2, and said extension terminates at its upper end in the connection 33 for the rope or other flexible member 34.

5 In operation a suitable set of jars or similar driving devices are secured to the end 23 of the member 17 and the flexible member 34 is also attached to the member 31, and the whole lowered into the well casing by 10 means of the rope or cable attached to the jars. Simultaneously with the lowering of the well-slitting device, the cable or rope 34 is also lowered and upon arriving at the desired point in the well casing, the flexible 15 member 34 is made fast, thereby suspending the device against movement. The jars are then set in operation and it will be evident that the driving action thereof will force the member 19 against the member 4, thus 20 causing the cutter wheels to perforate the well casing. In order to slot the casing, the flexible member 34 is released and the driving of the jars continued until slots of the desired length have been made. The device 25 is then raised by exerting pull on the rope or cable which is attached to the jars, and it will be evident that the cutting wheels will be drawn inwardly and out of engagement with the well casing due to the action 30 of the grooves in the member 17 co-operating with the flanges on the member 9. In this way it will be seen that the wheels will be flush with the face of the member 4 and permit the device to be easily raised to the desired point. Should it be desired to repeat 35 the cutting action on the part above the slots first made, it is evident that the member 34 is again made fast and the slotting operation is repeated.

40 While in the foregoing there has been shown and described the preferred embodiment

ment of this invention, it is to be understood that such changes may be made in the combination and arrangement of parts as will fall within the spirit and scope of the 45 invention as defined in the appended claims.

Having thus described my invention, I claim:

1. A device of the class described comprising a tubular member, a cylindrical member secured within the tubular member and provided with a central vertical tapering aperture, and transversely extending slots communicating with each other, cutter-wheel carrying blocks slideable in said slots, 50 a wedge member slideable through the central aperture in said cylindrical member, and means carried by said tubular member to hold the device in operative position within the well casing, said means also 55 adapted to be used to remove the device from the well casing.

2. A device of the class described comprising a tubular member, a cylindrical member secured within the tubular member and provided with a central vertical tapering aperture and transversely extending slots communicating with said aperture, cutter-wheels carrying blocks slideable in said slots, a wedge member slideable through 60 the central aperture, a cylindrical extension 65 formed at the lower end of the wedge member, and a disk secured to said extension forming a lower abutment for the device 70 when it is being put in place or removed 75 from the well casing.

In testimony whereof I affix my signature in presence of two witnesses.

FRANKLIN O. MACKEY.

Witnesses:

CHARLES BLENMAN,
HAZEL K. WHITEHEAD.
